UNITED STATES PATENT OFFICE.

JOHN JEPSON, OF WEST MERIDEN, CONNECTICUT, ASSIGNOR TO THE
MERIDEN BRITANNIA COMPANY, OF SAME PLACE.

DESIGN FOR TEA-SETS.

Specification forming part of Design No. 7,365, dated April 14, 1874; application filed March 18, 1874.
[Term of Patent 7 years]

To all whom it may concern:

Be it known that I, JOHN JEPSON, of West Meriden, in the county of New Haven and State of Connecticut, have invented a new Design for Tea-Set; and I do hereby declare the following, when taken in connection with the accompanying illustration and the letters of reference marked thereon, to be a full, clear, and exact description of the same, and which said illustration constitutes part of this specification, and represents a perspective view of the several pieces which constitute the set.

This invention relates to a design for tea-set; and consists in the peculiar form in outline, as shown in the accompanying illustration, whether as a set or in individual pieces.

The several pieces possess the same characteristic outlines. The body rests upon legs drawing or inclining inward. The body is in transverse section, of substantially egg shape, the smaller end resting upon the legs, the upper end crowned by an expanding neck, within which the cover, on such as require a cover, is

placed, as shown, and each provided with a spout or handle, or both, according to the use for which they are intended. The knob or tip of the cover is a transverse tipped bar crossing an upright crowned with a triangle, as shown in the illustration.

I do not wish to be understood as confining my design to the combined articles going to make up a set, but collectively or individually, as may be demanded.

I claim as my invention—

1. The design for tea-set, consisting of the egg-shaped body, flaring or expanding legs, and neck, as shown in the accompanying illustration and herein described.
2. The design for cover knob or tip, consisting of the transverse bar crossing an upright and crowned with a triangle, as shown and described.

JOHN JEPSON.
